(No Model.)

L. ROWLAND.
METHOD OF MAKING SHOVELS.

No. 432,331.

Patented July 15, 1890.

UNITED STATES PATENT OFFICE.

LYNFORD ROWLAND, OF CHELTENHAM, PENNSYLVANIA.

METHOD OF MAKING SHOVELS.

SPECIFICATION forming part of Letters Patent No. 432,331, dated July 15, 1890.

Application filed September 16, 1889. Serial No. 324,049. (No model.)

To all whom it may concern:

Be it known that I, LYNFORD ROWLAND, of Cheltenham, Montgomery county, State of Pennsylvania, have invented a new and use-

ful Improved Method of Manufacturing Shovels, of which the following is a true and exact description, reference being had to the accompanying drawings, which form a part of this specification.

10 My invention relates to the manufacture of shovels from sheet metal and with tubular sockets or tangs extending out from the back of the shovel to serve as or to receive a handle. Shovels of this kind have heretofore 15 been made by swaging the blade into shape and partially forming the socket between one pair of dies, and then completing the socket by bending the partially-formed tang into a tube by the operation of another set of dies 20 or by a hammer on a mandrel.

The object of my invention is to increase the rapidity and cheapness with which such shovels can be made; and my new process consists in forming the shovels from a sheet-metal blank by first swaging the blades to shape and partially forming the tang into a socket by the action of dies, as heretofore, and then completing the socket by passing the partially-formed tang between concavely-grooved 25 rolls.

Reference is now had to the drawings which illustrate my invention, and in which—

Figures 1 and 2 are respectively perspective views of the upper and lower dies for 30 swaging the blade to form and partially forming the tang. Fig. 3 is a central longitudinal section through the two dies; Fig. 4, a cross-section through that portion of the dies which acts on the tang of the blank, showing the form given to said tang in these dies. Fig. 5 is a side view of the rolls which I use to complete the tang and form it into a round socket, a shovel being shown under treatment in said rolls. Fig. 6 is a view of a sheet-metal blank such as I employ. Fig. 7 shows said blank after it has been subjected to the action of the dies shown in Figs. 1 and 2. Fig. 8 is a perspective view of the back of a shovel, showing the tang formed into a socket by the rolls; and 40 Fig. 9 is a perspective view of the rolls I employ in forming the sockets.

A is the upper die, having a projecting face

a corresponding in form to the face of the shovel to be formed, and a recessed portion a' corresponding to the outline of the desired 55 socket-tang on its upper face.

B is the lower die, having acting faces b and b' complementary to the faces of the upper die. The blank, such as is shown in Fig. 6, is placed between these dies and swaged to 60 the form shown in Fig. 7, the tang being given the shape in cross-section of an inverted U, as shown at F in Fig. 4. All this part of the treatment is, as already stated, old and in common use.

C and D represent rolls, having concave faces c and d and with a portion of their circumference recessed or cut away, as shown at c³ and d³. The acting face of the rolls between the ends c' c² and d' d² is equal in length, or 70 nearly so, to the extent of the tang to be operated upon, and the back ends c' and d' are flared, as shown, so as to give the lower edges of the tang the curvature shown at f in Fig. 8, as it merges into the back of the shovel-blade.

G represents the frame on which the rolls C and D are supported. Said rolls are of course driven in opposite directions, as shown by the arrows in Fig. 5. The actuating mechanism may be of any usual type, and is not shown in the drawings, save that cogs H and I are indicated as attached to the shafts of the rolls and gearing together, so that the rolls will maintain proper relative position.

E represents the blade of the blank or shovel, and F the tang or socket.

The blank having been swaged to the form given by the dies A and B, its U-shaped tang is introduced between the rolls C and D at 90 such time as their recessed portions come opposite and permit this insertion. As the rolls revolve, the curved face of roll D comes in contact with the downwardly-extending lips of the U-shaped tang, while its curved upper 95 side is held by the curved face of roll C, and the two rolls acting together shape the tang into a rounded socket, allowing its rear end, however, to flare, as shown at f, by reason of the flared formation of the back ends c' and d' of the roll-faces. It is not important, however, whether the shovel-blank be introduced to the rolls with its face up or down, as they can of course be made to operate properly.

upon it and close the socket-tube in either way.

The tubular socket can, as I have ascertained, be formed more rapidly and cheaply in the way above described than by the use of dies or mandrels, as heretofore, and the socket is completely formed by the rolls without distorting the curves given by the dies which perform the first stage of the operation, so that nothing remains after their action but to handle the shovels in the ordinary way.

Having now described my invention, what I

claim as new, and desire to secure by Letters Patent, is—

15 The method of forming the sockets of shovels, which consists in first striking the metal up into **U** form, and then finishing the socket by subjecting it to the action of the concavely-grooved rolling - dies, substantially as described.

LYNFORD ROWLAND.
